UNITED STATES PATENT OFFICE.

HORACE J. NICKETT, OF ATTLEBORO, MASSACHUSETTS, ASSIGNOR OF ONE-HALF TO ARTHUR R. KNOX, OF TAUNTON, MASSACHUSETTS.

HAT-PIN.

SPECIFICATION forming part of Letters Patent No. 723,781, dated March 24, 1903.

Application filed October 18, 1901. Serial No. 79,175. (No model.)

To all whom it may concern:

Be it known that I, HORACE J. NICKETT, of Attleboro, in the State of Massachusetts, have invented a new and useful Improvement 5 in Spring Hat-Pins, of which the following is a specification.

My invention relates to a hat-pin in which the ornamental head is connected with the stem by means of a spring, whereby the head 10 will have a tremulous movement when the hat is being worn; and my invention consists in the improved construction of the spring and its containing box, as hereinafter fully set forth.

15 In the accompanying drawings, Figure 1 represents an enlarged side view of a spring hat-pin embodying my improvement. Fig. 2 represents a longitudinal side section. Fig. 3 represents a longitudinal edge section. 20 Fig. 4 represents a section taken in the line 4-4 of Fig. 1.

In the drawings, *a* represents the stem of the pin; *b*, a double-ended connecting-head secured to the said stem.

25 *c* is a volute spring having its lower end secured in the bore of the connecting-head *b* and its upper end secured in the socket *d* of the ornamental head *A* of the hat-pin. The box *e*, which incloses the spring *c*, is made in 30 two parts *e' e²*, which are rolled together at

their edges *i*, as shown in Fig. 4, and provided with the opening *f* of sufficient extent to allow of the required movement of the arm *g* of the spring, whereby the ornamental head *A* of the pin may move from side to side and 35 up and down, so as to give the tremulous effect desired by the wearer, the lower arm *h* of the spring being rigidly held in the connecting-head *b*.

I secure the spring *c*, box *e*, and the stem *a* together by swaging the sides of the connecting-head *b* upon the same, as shown in the drawings. The employment of a volute spring inclosed in an ornamental box provides a desirable improvement in spring hat- 45 pins.

I claim as my invention—

In a spring hat-pin, the combination of the stem, and the connecting-head, with the volute spring held at one end by the connecting-head, the box inclosing the volute coil of the spring and having an opening at its edge for the loose movement of the free arm of the spring, and the ornamental head secured to the projecting end of the free arm, substantially as described. 55

HORACE J. NICKETT.
